TOY PARACHUTE

Arthur H. Vogt, Aurora, Ill.

Application March 3, 1937, Serial No. 128,850

3 Claims. (Cl. 46—86)

The invention aims to provide a new and improved toy parachute which may be easily and inexpensively manufactured and marketed and therefore sold at small cost, yet will afford a great deal of pleasure.

With the foregoing in view, the invention resides in the novel subject matter hereinafter described and claimed, description being accomplished by reference to the accompanying drawings.

Fig. 1 is a side elevation showing the manner in which the toy is propelled into the air, a suitable sling-shot being shown in dotted lines.

Fig. 2 is a side elevation at right angles to Fig. 1.

Fig. 3 is a longitudinal sectional view on line 3—3 of Fig. 2.

Fig. 4 is a transverse sectional view on line 4—4 of Fig. 1.

Fig. 5 is a fragmentary inner side view of the lower or rear end of the pivoted cover.

Fig. 6 is a disassembled perspective view.

Fig. 7 is a side elevation illustrating the toy substantially as it appears during descent.

A preferred construction has been illustrated and will be specifically described, with the understanding however, that variations may be made within the scope of the invention as claimed.

In the drawing above briefly described, the numeral 8 denotes an elongated flat cradle plate upon which to longitudinally rest a toy parachute 9 when the latter is in rolled form as seen in Figs. 1 and 3, said cradle plate 8 having a weighted nose 10 at its front end and being provided with a laterally bent rear end providing a wall 11 to abut the rear end of the folded and rolled parachute 9. The nose 10 is preferably formed by casting a quantity of lead or other suitable metal upon the front extremity of the cradle plate 8, and said nose is provided with a lateral hook 12 for engagement with a sling-shot or the like 13 used for propelling the toy into the air. The usual lines 14 of the parachute 9 are secured to the plate 8 and provision is made for holding the rolled parachute 9 against said plate while the toy is being impelled, and during the flight into the air produced by the impelling means 13, the means holding the parachute against the plate 8 being then released however, freeing the parachute and allowing it to open as the toy descends. The flat form of the cradle plate 8 insures that the rolled parachute shall readily leave said plate when the holding means is released. I prefer to make use of a longitudinally

channeled cover 15 for holding the rolled parachute in place against the cradle plate 8, the front end of said cover being pivoted to said cradle plate by means of a pivot pin 16 passing through the front corners of the cover and passing also through lateral lugs 17 which project from the longitudinal edges of the cradle plate 8 in the same direction as that taken by the lateral wall 11. The cover 15 is preferably of such length that its rear end projects beyond and partially receives the wall 11 to prevent said wall 11 from resisting the flight of the toy, said rear end of said cover and said wall being provided with flexible tabs 18 and 19 respectively, to be held together with one hand while the sling-shot or the like 13 is operated with the other. I prefer to use tubular rivets 20 and 21 in securing the tabs 18 and 19 to the cover 15 and wall 11 respectively, and said tabs may be of leather or other preferred material. By holding these tabs together with one hand while operating the sling-shot or the like with the other, it is insured that the rolled parachute 9 shall be held in proper place prior to propelling the toy into the air, and as long as it is in flight, the air pressure against the cover 15 holds it closed. As soon as the propelling force is expended however, the toy reverses its position and the cover 15 swings outwardly, releasing the parachute 9 with the result that this parachute opens as the toy descends, producing a very realistic appearance.

It is preferable to make use of a rubber band 22 to aid in opening the cover 15. This rubber band is looped around the cradle plate 8 in front of the lugs 17 as shown at 23, extends over the pivot pin 16 and extends rearwardly at the inner side of the cover 15. A portion of the band extends outwardly through the tubular rivet 20 as seen most clearly in Figs. 3 and 5 and is looped at 24 around the secured end of the tab 18. The band 22 is, of course, tensioned and its tension serves to outwardly swing the cover 15 when the air pressure against said cover is sufficiently diminished due to slowing down or stopping of the toy at the end of its ascent. To insure that proper air pressure shall be attained to hold the cover 15 closed until the proper time, said cover preferably increases in width toward its rear end as shown, and this is also preferably true of the cradle plate 8. The widened rear end of this cradle plate and the adjacent portion of the lateral wall 11 may well be formed with openings 25 through which the lines 14 may be passed and tied, to connect said lines with said cradle plate.

By providing the novel construction shown and described, a toy is provided which may be easily and inexpensively manufactured and marketed, and may therefore be sold at small cost, yet it 5 will afford a great deal of pleasure and may be repeatedly conditioned for re-use after any flight and descent, simply by re-rolling the parachute 9, laying it upon the cradle plate 8, and closing the cover 15.

10 The details disclosed have proven to be of advantage from numerous standpoints and are therefore preferably followed. However, attention is again invited to the possibility of making variations within the scope of the invention as 15 claimed.

I claim:

1. A toy to be propelled into the air, comprising a parachute in rolled form, a flat elongated cradle upon which to longitudinally place the rolled 20 parachute, the parachute lines being secured to said cradle plate, the rear end of said cradle plate being provided with a lateral wall to abut the 25 rear end of said rolled parachute, a weight secured to the front end of said flat cradle plate and having means to engage a propelling device, a longitudinally channeled cover having its open side disposed toward said flat cradle plate to hold 30 said rolled parachute against said flat cradle plate, the front end of said channeled cover plate being transversely pivoted to the front portion of 35 said flat cradle plate, the rear end of said channeled cover plate being sufficiently wide to receive the outer end of said lateral wall, and rearwardly projecting tabs secured to said wall and said rear end of said cover to be held by one hand while the propelling device is being operated with the other hand.

2. A toy to be propelled into the air, comprising a parachute in rolled form, a flat elongated 40 forwardly tapered sheet metal strip upon which

to longitudinally place the rolled parachute, the 5 parachute lines being secured to said strip near the rear end of the latter, said rear end of said strip being bent laterally to provide a lateral wall to abut the rear end of said rolled 10 parachute, a weight secured to the front end of said flat strip and having means to engage a propelling device, a second elongated sheet metal strip bent into transversely channeled form to provide a channeled cover having its open side 15 disposed toward said flat strip for holding said rolled parachute against said flat strip, said channeled cover being forwardly tapered and having its front end transversely pivoted to the front portion of said flat strip, the rear end of 20 said channeled cover being sufficiently wide to receive the outer end of said lateral wall, and rearwardly projecting flexible tabs secured to 25 said wall and said rear end of said cover to be held by one hand while the propelling device is 30 being operated with the other hand.

3. A toy to be propelled into the air, comprising two elongated parachute-holding members, a transverse pivot pin between and connecting the front portions of said members, tabs projecting 25 rearwardly from the rear ends of said members, one of said tabs being secured to one of said members by means of a tubular rivet, and a tensioned rubber band passed transversely across the front side of said pivot pin, one of the looped end portions of said rubber band being passed outwardly through said tubular rivet and looped around the tab held by said rivet to anchor this looped end of the band, the other looped end of said band being extended laterally with respect to said 35 pivot pin and looped around the front portion of the other of said members, whereby said tensioned band will relatively open said members when wind pressure against the latter is relieved.

ARTHUR H. VOGT. 40
